UNITED STATES PATENT OFFICE

WILLIAM H. BANKS, OF WINTHROP, MASSACHUSETTS

DIRIGIBLE AIRSHIP

Application filed March 29, 1927. Serial No. 179,366.

This invention relates to a new and useful improvement in ships. It is more especially intended for application to dirigible airships but is not limited to airships in its broader aspects.

It is well known that the conventional form of dirigible balloon or airship is unwieldy and in its travel through the air presents such a large surface area to the air resistance that great power is required to overcome the said resistance. It is also well known that with the conventional form of construction and poise of dirigibles a very rigid and strong construction is necessary to withstand the unequal strains exerted by adverse air currents and by gravity and that the great weight resulting from such construction requires abnormal means for making it buoyant. One object of the present invention is to reduce the air resistance and to equalize the air pressure on the sides.

Another object of the present invention is to produce a ship of relatively light weight and large capacity. Another object is to so construct the ship as to present a relatively small portion of the surface area to adverse vertical air currents, and to concentrate the weight so that gravitation will exert its downward force in a direct line with the uplifting power or the buoyancy thereby reducing to the minimum unequal strains from adverse currents and from gravitation. Another object is to construct the dirigible of such form as to lessen the extent to which rain, snow, fog or mist will collect on the surface of the ship, and which add greatly to the weight which has to be overcome.

Another object is to reduce the rudder resistance to sudden changing of the course. It is well known that the conventional dirigible being subject to unequal pressure sometimes does not respond to its rudder pressure and deviates from its set course to a considerable degree, taking on a pitching and swaying motion thereby causing a strain and dissipating its power. One object of the present invention is to provide means consisting of worm directional-propellers to stabilize the directional course of the dirigible. Another object is to so construct the ship and regulate

its poise as to make landing easy and to render it less liable to injury when it is at rest on the land or made fast to a mooring.

The invention will be fully understood from the following description when taken in connection with the accompanying drawings and the novel features thereof will be pointed out and clearly defined in the claims at the close of this specification.

In the drawings:

Fig. 1 is a side elevation of an airship embodying the invention.

Fig. 2 is a rear elevation of the airship shown in Fig. 1.

Fig. 3 is a section on line 3—3 of Fig. 2.

Fig. 4 is a plan section on line 4—4 of Fig. 1.

Fig. 5 is a fragmentary detail view of the inner periphery of one of the revolving cylinder sections.

Fig. 6 is a section on line 6—6 of Fig. 5.

Fig. 7 is a section on line 7—7 of Fig. 1.

Fig. 8 is a vertical sectional view on line 8—8 of Fig. 2.

Fig. 9 is an enlarged plan section on line 9—9 of Fig. 1 showing a portion of one of the cylinders and one of the buckets and the chain take up for the brake.

Fig. 10 is an enlarged vertical section on line 10—10 of Fig. 9.

Fig. 11 is a detail view showing a modification of one of the cylinder sections shown in Fig. 8.

Referring now to the drawings, there is shown the hull or frame of the airship which should be made as light as possible consistent with strength. Preferably it has hollow beams of sheet metal. The frame is preferably somewhat diamond shape in plan view as shown in Fig. 4, thus being symmetrical and pointed both endwise and laterally. As viewed in Figs. 1 and 4 the right hand end is the bow of the ship.

In order to present as little resistance as possible to the air pressure both in its forward travel and in its elevation and to the pressure of the vertical air currents, the beams which form the framework are so shaped as to present a wedge like edge as shown at 22 to the air both on the side edges

and on the top. There are shown at 20 the inclined beams of the hull and the struts 21 all made hollow and having wedge like edges 22 for the purpose previously described. The 5 under faces are preferably plane.

There is provided a rudder 24 for use in controlling the elevation and a rudder 25 for steering the course of the ship. There are provided two opposite side propellers 26, 26 10 and a rear propeller 27 driven by motors 28 or other suitable power mechanism through suitable connections for the forward drive of the ship and there are forward and aft elevational propellers 29, 29 driven by motors 30.

One of the main features of the invention 15 consists in the vertical rotary cylinder B which operates somewhat after the so called Magnus effect, but is of different construction from anything heretofore known for equalizing the pressure on both sides of the cylinder as will be hereinafter described. There may be employed one or more such cylinders as desired, for instance one forward and one aft. In the construction shown in the drawings only one cylinder is employed, this being located amidships. The word "cylinder" is intended herein to include the entire combination cylinder from top to bottom, but is composed of several sections rotatable independently of each other as will be hereinafter 25 described.

A vertical mast C is fixedly mounted in the ship rising from and resting upon the bottom portion 31 of the frame.

The mast is stepped in a socket 19 and extends vertically upward through the cylinder B, axially thereof. The mast is preferably made of metal and of skeleton form so as to give it strength and rigidity with a minimum 40 of weight.

The deck is of skeleton or grid form comprising the hollow beams 32 forming the four side rails of the diamond shape frame and the horizontal brace members 33 which extend 45 centrally inward toward the mast from the apices of the four corners of the diamond shaped frame, said members 33 being connected at their inner ends with an annular member 34 from which they radiate. The 50 side frame members 32, annular member 34 and connecting brace members 33 constitute a sort of deck. At the ends and two sides the inclined beams 22 extend from the bottom 31 to the apices of the main deck and help 55 support the said deck.

The cylinder B extends upward through the said annular central member 34, and is thereby partially supported against swaying. The cylinder is further steadied by guy 60 wires or cables 35.

The cylinder B comprises a plurality of tubular sections or shells one above the other independently rotatable on their axes. The alternate sections are rotatable in opposite 65 directions, one set of said sections rotating in

a clockwise direction and the other set rotating in a counterclockwise direction for the purpose of maintaining the poise as will be hereinafter described. There should be an equal number of oppositely rotating members. The said sections are therefore in 70 multiples of two and may be as many in number as desired according to the height of the entire cylinder or stack and the desired length of the cylinder sections. As shown in 75 the drawings there are four of such sections B¹, B², B³, B⁴.

Each cylinder section is supported at its lower and upper ends by a member 36 secured to the mast and extending laterally outward 80 therefrom to provide end seats on which the cylinder section rotates. Anti-friction bearings are provided at each end of each section.

To provide for the anti-friction bearings 85 the seat members 36 are formed with annular grooves or raceways 37 cooperating with annular grooves or raceways 38 in the ends of the cylinder sections to receive balls 39 spaced apart from each other by spacing members 40 in well known manner. The cylinder sections are each free to rotate or spin on their 90 axes independently of each other.

The bottom supporting members for the 95 upper pair of cylinder sections B⁴ and B³ are of spider form having a hub 41 made fast to the mast and connected by spokes or ribs 42 with the annular rim member 36 which constitutes the seat and in which the raceways 37 are formed.

The supporting member 43 for the lower 100 end of the cylinder section B² which is the first of the cylinder sections above the deck frame members 33 preferably extends across the lower end of said cylinder section B² instead of being of skeleton or grid form like those for the two upper cylinder sections B³ and B⁴. It has a lateral flange extension 105 provided with a raceway of the form shown in Fig. 10 already described. A vertical tubular member 44 extends down from said support 43 and rests on the floor 31 of the ship. This tubular shell portion 44 is shown as provided with horizontal partitions for dividing it into compartments 45, 46 to be 110 utilized for storage or any other purpose desired. One of these partitions 47 has a lateral flange extension below the deck having a raceway for cooperating with the raceway on the upper end of the lowermost cylinder section 115 B¹ and the bottom member 31 has a raceway for the lower end of said section B¹ for the reception of ball bearings as already described with relation to the two upper cylinder sections. 120

A cylinder D to contain the gas bags is enclosed within the rotatable cylinder sections but is separate therefrom. Preferably it is made of meshwork. Vertical stiffening rods 48 and annular spider members 49 to- 125

gether with the stationary spider members support the said meshwork cylinder D.

Gas bags 50 which contain lighter-than-air gas to enable the ship to rise are packed into this cylinder D to give buoyancy to the ship.

5 The outer cylinder B made up of the several cylinder sections functions in part like the skin of the ordinary dirigible which encloses the gas containers.

10 Each rotary cylinder section is provided with scoops or buckets 51 in turbine fashion on its outer periphery which extend outwardly to catch the air pressure and are carried around by the rotating cylinder members.

15 The scoops or buckets on alternate cylinder sections have their mouths open in opposite directions, that is, the buckets carried by the sections B² and B⁴ have their mouths facing in the opposite direction from those carried by the cylinder sections B¹ and B³.

20 The purpose of this is to cause the alternate sections to rotate in opposite directions, one set rotating clockwise and the other set rotating counterclockwise. It is well understood that as the ship moves through the air the currents of air will be split, a part going on one side and a part going on the other side of the cylinder. According to the well known Magnus effect, there is less friction or 25 resistance on the side that is moving with the air than on the opposite side which rotates against the air pressure. If all of the cylinder sections rotate in the same direction the pressure will be greater on one entire side 30 of the cylinder than on the other side and tends to tip the cylinder into an inclined position. The purpose of having the alternate cylinders equal in number and rotate in opposite directions is to equalize the pressure and thus prevent tipping.

40 By making the outer cylinder B in sections in vertical and axial alignment with each other and having the buckets on alternate sections thereof face in opposite directions as hereinbefore described so that some cylinder sections of each stack rotate in one direction and at the same time other sections of the same stack rotate in the reverse direction, the cylinder is thereby stabilized.

45 By making the alternate cylinder sections to rotate in opposite directions to each other the air pressures at right angles to the direction of flight are equalized and equilibrium is maintained.

50 It is important that the center of gravity be kept very low.

Brakes are provided which may be operated to retard the speed of rotation of either or both sets of cylinder sections independently of each other in order to still more accurately govern the pressure.

A brake band 52 encircles the upper cylinder section B⁴, the ends of the brake band being connected with sprocket chains 53 which are connected at one end to a sprocket

wheel 54 mounted on a vertical brake rod 55 having at its lower end a hand wheel 56 whereby the brake rod may be rotated to tighten or loosen the brake band. The brake band is attached to a link 57 pivoted to the raceway flange of the cylinder diametrically opposite the sprocket.

70 A brake band 58 is also provided for the next lower cylinder section B³ and is operated by a brake rod 59 having a hand wheel 60. The brake rod 59 is tubular and the brake rod 55 passes loosely through said tubular rod 59. Guides 61 for the brake band are provided to keep it from sagging at the sides intermediate the connections with the brake rod and with the links 57.

75 The inner face or envelope of each of the rotary cylinder sections is preferably formed with cells 62 as shown in Figs. 5 and 6 to increase the strength without unduly increasing the weight.

80 The conventional dirigible being subject to unequal pressure is thereby at times caused to disregard its rudder pressure and to deviate from its set course to a considerable degree and from that cause to take on a pitching and swaying motion, thereby straining itself and dissipating its power. In order to obviate this trouble I provide directional worms or 85 screws which are given a revolving or spinning motion by the air pressure during the forced passage of the dirigible through the air in flight, augmented by power from the power plant or motor of the ship to give it a grip, as it were, on the air, the power from the motor being releasable at will to make it easier to change the course of the ship.

90 In carrying out this idea there are provided, as shown in the drawings, two worm propellers 64, 64 located above the deck on opposite sides of the cylinder and parallel with each other and with the horizontal axis of the ship. These worms are each mounted upon a shaft 65 having driving connection with a motor 66. The worms are rotated by 95 the air pressure augmented by the ship's power as the ship is in flight. The motors may be controlled so as to shut off both or either one independently as may be needed to compensate for any unequal pressure of the air on opposite sides of the ship.

100 A cap 67 is provided to cover the top of the cylinder, has a flange extension which overhangs the outer periphery to prevent the whirling air currents around the cylinder from escaping at the top, the escape of which would diminish the effect of the rotating cylinder, and the cap also prevents the air above the cylinder from being drawn down by the suction which would further tend to deflect 105 the whirling currents and diminish their effect.

110 In the modification shown in Fig. 11 the anti-friction bearings for the cylinder sections are located immediately adjacent the 115

mast and near the axis of the cylinder instead of at the outer periphery of the cylinder. In this construction, hubs 70 are secured to the inner ends of the arms 71 of the cylinder sections and have raceways therein which co-operate with raceways formed in blocks 72 made fast to the mast to hold the balls. The hubs 70 are loose on a cylindrical sleeve 73 made fast to the mast and are rotatable on 10 said sleeve. In this form of construction there is no need of the meshwork cylinder D. The gas bags may be held directly in the cylinder sections and be carried around therewith. A sleeve 74 is provided attached to the 15 hubs 70 to keep the gas bags from rubbing against the mast. The preferred method, however, is to have bearings at the rim as previously described.

The pressure of the air on the rotating cylinder causes the wall of the cylinder to assume a slight concave surface thereby more thoroughly resulting in the Magnus effect by regarding the escape of revolving air current.

While the invention has been especially described as embodied in an air ship, some of its more important features, especially the rotary cylinders, are adapted for embodiment in sea going ships. It is therefore intended that the claims so far as they relate to features which are applicable to the construction of ships which operate on the water as well as to air ships, shall cover both kinds of ships.

The invention may be embodied in cylinders employed in connection with any other structure in which the cylinder is exposed to great air pressure on its sides, for instance vertical stationary cylinders which are exposed to high winds, and it is my intention that the 40 claims shall cover broadly a sectional cylinder embodying the invention, whatever the particular location or use of the cylinder.

What I claim is:

1. A dirigible airship having power means for positively driving the ship in a forward direction through the air, a cylinder mounted in a vertical position on said ship, gas containers within said cylinder containing lighter than air gas, said cylinder being rotatable on 50 its vertical axis and a plurality of buckets projecting laterally from said cylinder adapted to receive the air resisting pressure against their front faces whereby said cylinder will be rotated on its axis counter to the forward 55 movement of the ship and reduce the resistance of the cylinder to the pressure of the air as the vessel is propelled through the air by its motor.

2. A dirigible airship having power mechanism for positively driving the ship through the air in a forward direction, a cylinder consisting of a plurality of tubular shells in axial alignment with each other and mounted in vertical position on said ship, gas containers 65 in said shells containing lighter than air gas,

each of said shells being rotatable on its axis independently of the rotation of certain other of said shells, each shell having blades projecting laterally therefrom to receive the resisting air pressure against the front face of the blade and thereby rotate the shell on its axis counter to the forward movement of the ship while the ship is being propelled forward by said motor, the blades on one or more of the cylinder sections being so disposed with relation to the blades on certain other sections that one or more of said sections will be caused to rotate in the opposite direction to the rotation of certain other of said cylinder sections at the same time.

3. A dirigible airship having power mechanism for positively driving the ship, a cylinder consisting of a plurality of tubular shells in axial alignment with each other and mounted in a vertical position on said ship, gas containers within said cylinder containing lighter than air gas, each of said shells being rotatable on its axis independently of certain other of said shells, each shell having mechanism adapted to be actuated by the resisting air pressure whereby the shell is rotated on its axis during the forward movement of the ship while the ship is being propelled by the power mechanism, the said mechanisms which are actuated by the air pressure to rotate the shells during the movement of the ship being so constructed and arranged on the different shells that some of said shells will be caused to rotate in the opposite direction to certain other of said shells and simultaneously therewith.

In testimony whereof I affix my signature.
WILLIAM H. BANKS.
